UNITED STATES PATENT OFFICE.

ADELMER M. BATES, OF CHICAGO, ILLINOIS; ASSIGNOR TO BATES VALVE BAG COMPANY, OF CHICAGO, ILLINOIS; A CORPORATION OF WEST VIRGINIA.

MACHINE FOR FILLING AND WEIGHING BAGS.

Application filed March 22, 1920. Serial No. 387,888. Renewed May 6, 1925.

To all whom it may concern:

Be it known that I, ADELMER M. BATES, a citizen of the United States, residing at Chicago, in the county of Cook and State 5 of Illinois, have invented a certain new and useful Improvement in Machines for Filling and Weighing Bags, of which the following is a specification.

My invention relates to improvements in machines for making and filling bags and has for one object to provide a new and improved form of machine whereby the bags may be made and filled with material under pressure, the pressure being preferably exerted by a so-called screw packer. An other object of my invention is to provide an arrangement whereby the bag may be filled by the screw packer and also whereby the bag may be properly weighed and a proper amount of material fed into it independent of the operation of the packing. In other words, the packer is a heavy cumbersome high pressure apparatus which tends to exert a downward pressure on the bag and thus make weighing impossible, and I have provided with it a separate weighing and feeding arrangement whereby the bag may be filled by the screw packer and at the same time, the contents properly weighed. Other objects will appear from time to time in the specification.

My invention is illustrated, more or less diagrammatically, in the accompanying drawings wherein:

Figure 1 is a side elevation with parts in section, of the upper portion of the machine drawn at the same scale as Figure 2;

Figure 2 is a side elevation with parts in section, of the lower portion of the machine drawn at the same scale as Figure 1;

Figure 3 is a section on an enlarged scale through a portion of the upper end of the machine;

Figure 4 is a section on an enlarged scale through a portion of the lower end of the machine;

Figure 5 is a section along the line 5—5 of Figure 1;

Figure 6 is a section along the line 6—6 of Figure 1;

Figure 7 is a detail of the clutch operating trip fingers;

Figure 8 is a section on the line 8—8 of Figure 2.

Like parts are indicated by like characters throughout all the drawings.

A' is a supporting scale box frame, A' a scale platform projecting upwardly there-thru, supported by a series of scale levers A⁷, which communicate with a scale arm A², having a weight A³ adjustable therealong; A⁴ is a carriage mounted for longitudinal movement along the box frame and adapted to be moved therealong, by the screw A⁵ engaging the nut A⁶ and driven by the reversing pulley arrangement A⁸ from the countershaft A⁹ which is in turn driven by the belt A¹⁰ from any suitable source of power not shown. The countershaft A⁹ also drives by the belt A¹¹ a splined shaft A¹² upon which is slidably mounted the worm gear A¹³ held between lugs A¹⁴ on the carriage A⁴ and in mesh with a gear A¹⁵ which in turn operates the sewing mechanism in a sewing machine A¹⁶ on the carriage A⁴. A¹⁷ is a cutting disc or knife mounted on the sewing machine A¹⁶ and about it are a pair of reciprocating needles A¹⁸ suitably connected in any preferred manner with the driving mechanism. A¹⁹ is an extension from the sewing machine A¹⁶ adapted to hold the bag in opposition to the sewing needle and to compress the opposed bag surfaces for the sewing and severing operation.

B is a supporting platform above the weighing and sewing mechanism. B' is a hollow frame above an opening in such platform. The frame B' serves as a mandrel on which is formed the fabric tube that later is formed into the separate bags. B² is a roll of bag forming fabric, B³ a convex and B⁴ a concave shaping roll, these rolls are so spaced that there is just room between them for the bag fabric to pass through and they are so arranged that they start the folding of the fabric about the tube or mandrel B'. The roll B⁴ is spaced from the tube B' so that there is just room for the sheet of fabric B² to pass between them. The fabric is then drawn up and

- around the tube so that its opposed edges can be drawn together and stretched around the tube by the rollers B^s which hold the edges together for the sewing machine B^s which forms the tube which is then drawn up by the rollers B^t and passes around the rounded upper end of the mandrel down into its interior around the filling tube B^r , the tube is drawn down along the tube B^s by the rollers B^o which engage the fabric tube and press it against an enlarged portion of the filling tube and feed it down toward the storage space where the tube is shown puckered up ready for use. The sewing machine and the two sets of feeding rollers are driven by belts as shown from a suitable source of power such as instance as the electric motor as shown.
- At a point above the weighing plat-
- 20 form, the feeding tube is enlarged as at C , and there is a spring girdle C' encircling the tube at that point to hold back the fabric tube and limit the downward flow of the bag fabric. The filling tube terminates 25 a short distance below this enlargement so that material may be discharged into the end of the bag tube at a point below the lower limit of the storage zone defined by the spring girdle. C^s is a bag supporting 30 grid or platform. It is carried by a slide-able rod C^s counterbalanced by a weight C^t on the end of a cable C^s , the weight of the counterbalance being great enough to overcome the weight of the grid when there is 35 no filled tube on it but not great enough to support the loaded platform and tube. The girdle C' is slidably mounted on the rod C^s , but in frictional engagement therewith, so that while normally fixed thereon, it will 40 slide therealong in response to sufficient pressure or tension. As the rod C^s is lifted, the girdle C' normally lifts with it, but may be drawn down by the pressure applied to the bag tube passing within it. C^s is a rack 45 associated with and adapted to move with the rod. It is in mesh with a gear C^r driven by a belt C^o from the countershaft C^s and clutch C^{10} so that when the toggle joint is in the position as shown the clutch is dis-
- 50 engaged and the gear is not driven and when the toggle is closed power applied to the pulley C^{11} drives the gear.
- The toggle joint D which controls the drive of the rack C^s is actuated by the slide-able bar D' carried by the upright D^s . At the end of the bar is a pivoted link D^s free to move up into a vertical position but held against downward movement below the horizontal by the lug D^t . This link carries 55 a roller D^s adapted to be engaged by the cam D^e as the rack passes down to throw out the clutch, and adapted to swing back out of line when it is engaged by the top of the cam D^e but to be engaged by the working surface of the cam on a downward
- movement of the rack to engage the clutch and thereby provide a driving power to continue such downward movement. D^s is an automatic latch adapted to hold the bag supporting grid in the lower position once 60 it has been forced there by the gear and rack until the operator releases it to permit reverse movement under the urge of the counterweight.
- The filling tube B^s is supported within 70 the tube B' by the frame E which is clear of the top of the latter tube so as not to interfere with the passage of the bag fabric. E' is a filling hopper mounted on the upper end of the filling tube and E^s a feed spout 80 which discharges into it. E^s is a hollow combined feeder shaft and finish feed tube passing down within the feed tube. It terminates at its lower end in a screw conveyor E^t which is adapted to force the material 85 fed into the tube out into the bag tube surrounding its end when it is rotated. This screw packer might extend up further in the tube, but the arrangement shown is quite enough to pack the material into the tube 90 and to exert a sufficient pressure in a downward direction to cause the bag supporting grid to move down to throw the clutch to start the downward feed of gear and rack after a sufficient quantity of material has 95 been forced into the tube. The feeder shaft is rotated by a sprocket chain E^s driven by the shaft E^o which is in turn driven from any suitable source of power by the belt E^r through a clutch E^c controlled by a toggle joint E^s and slide rod E^{10} with a roller E^{11} at its end. This roller is adapted to be drawn over to disengage the clutch by the downward movement of the cam E^{11} , and 100 to be forced back to engage the clutch by the cam E^{12} when the grid C^s returns to its upper position. E^{11} is a shutter controlled by the control rod E^{11} , spring held lever E^{12} and pull rope E^{13} whereby the operator after 105 the force feeder has done its work and ceased its action, can close it off so as to prevent the dropping into the bag during the weighing operation of any material from the force feeder which might if not prevented disturb the weighing operation. 110
- After the force feed apparatus has done its work and the grid has descended till the tube rests on the scale platform, the operator starts the electric motor F which drives the screw conveyor F^s and feeds a supply of material from the chute F^2 to discharge it 115 into the finish feed tube F^s whence it drops down to the sieve F^s which comprises two parallel perforated plates F^4 one of which is fixed, the other being rotated by the shaft F^o which is driven by the miter gears F^r from the screw conveyor shaft, the arrangement being such that as soon as the scale is 120 counter balanced by the desired weight of material, the operator will stop the motor, 125 130

rotation of the sieve will cease and no further feed will take place.

It will be evident that while I have shown in my drawings an 'operative' device, still 5 many changes might be made in size, shape, and arrangement of parts and I wish therefore, that my drawings be regarded as in a sense, diagrammatic.

I have shown my apparatus arranged to 10 take the fabric from a roll to make it into a tube and fill and form bags therefrom. Obviously with only a slight difference in adjustment, a tube made on some other machine might be threaded onto the filling 15 tube and filled in exactly the same manner, the bags being separately filled and cut off from the end thereof and even without any difficulty, it would be possible to thread separate previously formed bags onto the filling tube and fill them in exactly the same 20 way as the tube is filled to form the bags.

The use and operation of my invention are as follows:

The operation of the bag tube forming 25 part of the apparatus is continuous, and the rate of feed is such that the bag fabric will be drawn off the storage roll fed between the concave convex rolls and started about the forming tube, its edges will be drawn 30 together and sewn and the formed tube will be drawn up toward the end of the forming tube and then drawn down thru it to be fed to the storage zone where it is puckered about the filling tube so that there will always 35 be a supply of bag tube more than is needed to supply the normal rate of demand of formed bags, the idea being that unless there is some slack at all times between the tube filling and weighing and the 40 tube forming operations, the weighing will be interfered with and the sewing apparatus will be unable to do a good job of sewing on the tube.

Starting with the lower end of the bag 45 tube sewed across and in the position shown in dotted lines in Fig. 2 the lower feed control cam will throw the clutch in and the screw packer will be operating to force material down into the end of the bag tube, 50 this will cause the tube to move slowly downward carrying the grid and associated parts with it at a rate governed by the rate at which the packer is forcing the material into the tube. This will continue until the 55 lower cam on the rack throws the drive clutch in and starts the gear drive to forcing the grid down. At about the same time as this takes place the uppermost cam will throw the feed clutch out and the operation 60 of the screw packer will cease. The downward movement of the tube and grid will continue until the automatic latch goes into operation and locks the grid down with its upper surface below the upper face of the 65 scale platform and with the tube resting on

the scale. At the same time the upper drive cam will throw the clutch out and thus the tube feed will be stopped and the tube is ready to be weighed.

With the bag resting on the scale, the operator will start the finish feed and as the screw conveyor feeds the material into the finish feed tube, the sieve will rotate to provide a gentle flow of material which will be sufficiently slow and even not to interfere 70 with the accuracy of the weighing operation, and which can also be turned off instantaneously when the amount fed in is enough to counterbalance the weight set on the scale beam.

The force feeder is a large and heavy device adapted to feed large quantities of material at a relatively low velocity but at high pressure and when its operation ceases there is sure to be a certain amount of material 80 left in the system and the only way to be sure that some of this does not drop into the filled tube and cause inaccurate weighing is to provide the shutter as indicated 90 which may by the hand of the operator be thrown up to close the screw feeder while the finish feed is working. I have shown only a hand pull rope for this but clearly any arrangement might be used. The essential thing however is that the closure for the force feed must be at the extreme lowest point so that nothing that is contained in the force feed system when the force feed stops can by any chance get into the tube while it is being weighed.

After the proper amount of material has been fed to and weighed into the tube, and the feeding process has stopped, the operator will start the sewing machine and the feed screw will drive it across the width of the bag sewing up the tube above the charge therein. This machine is normally a two needle machine so that it makes two parallel seams, and it will also normally be provided with a knife so arranged that as the seams are made the bag fabric will be cut between them and the filled bag will thus be formed from the tube and the tube will be left with a closed end ready for another load.

At this time the operator will throw the bag off the grid and release the latch. The weight of the counterweight will raise the grid and associated parts until the end of the tube will be back in the dotted line position of Fig. 2. The rod rises, and at the same time the frictional contact of the rod with the sleeve associated with the spring girdle will cause the girdle to travel up the feeding tube to draw the closed tube end up to the position it is to assume when the filling action starts. The puckered bag tube will of course offer no resistance of any consequence to this movement of the girdle, and as the tube is filled and drawn out the girdle will move down to the position shown.

on Fig. 2 after which the puckered bag tube will be drawn out as it is needed in the operation.

I claim:—

5. 1. Apparatus for filling and weighing bags, which comprises a filling tube, means for holding a bag with the discharge end of the tube inside of and near the closed end of the bag, means for forcing material out through the tube, compacting it against the end of the bag, and thereby forcing the bag off of the tube, weighing means, and automatic mechanism acting, when the bag has been forced to a fixed point, to move it from that point and place it on the weighing means.
10. 2. Apparatus for filling and weighing bags, which comprises a filling tube, means for holding a bag with the discharge end of the tube inside of and near the closed end of the bag, means for forcing material out through the tube, compacting it against the end of the bag, and thereby forcing the bag off of the tube, weighing means, and automatic mechanism acting, when the bag has been forced to a fixed point, to move it from that point and place it on the weighing means, and separate means for supplying additional material to the bag while it is on the weighing means.
15. 3. Apparatus for filling and weighing bags, which comprises a filling tube, means for holding a bag with the discharge end of the tube inside of and near the closed end of the bag, means for forcing material out through the tube, compacting it against the end of the bag, and thereby forcing the bag off of the tube, means responsive to the movement of the bag for discontinuing the force feed upon the bag reaching a fixed point, weighing means, automatic mechanism acting, when the bag has been forced to a fixed point, to move it from that point and place it on the weighing means, and separate means for supplying additional material to the bag while it is on the weighing means.
20. 4. Apparatus for filling and weighing bags, comprising a filling tube adapted to receive a bag thereabout with the closed end of the bag near the discharge end of the tube, means for forcing material through the tube and out of its discharge end into the bag, means for resisting the movement of the end of the bag, including means for applying tension to the walls of the bag, weighing means, and automatic means for releasing the tension on the bag walls when the bottom of the bag reaches a predetermined distance from the end of the filling tube.
25. 5. In a bag filling and making apparatus, a filling tube adapted to have bag tubing positioned thereabout, means to form transverse closures across the tubing beyond the tube, means to feed material through the tube into the tubing; detention means adapted to surround the tubing and the tube and yieldingly resist the movement of the tubing from the tube, means for reciprocating said detention means longitudinally of the tube.
30. 6. In bag filling and making apparatus, a filling tube adapted to have bag tubing positioned thereabout, means to form transverse closures across the tubing beyond the tube, means to feed material through the tube into the tubing; detention means adapted to surround the tubing and the tube and yieldingly resist the movement of the tubing from the tube, means for weighing the filled end of the tubing, and means operatively connected with said weighing mechanism for reciprocating said detention means.
35. 7. In bag making and filling apparatus, a substantially vertical filling tube adapted to have tubing positioned thereabout and freely slideable therealong, detention means adapted to surround the tubing and tube and to yieldingly resist extension of the tubing, and means for reciprocating said detention means longitudinally of the tube.
40. 8. In apparatus of the class described, a feeding tube having therethrough a central passage and a second passage surrounding said central passage, separate means for feeding materials through said passages, and automatic means, operating only the means feeding through said surrounding passage until the bulk of a charge is fed, and then stopping the same, and manually controlled means for operating only the means feeding through the central passage to complete the charge.
45. 9. In apparatus of the class described, primary feeding means for forcing into a package an annular stream of material, secondary feeding means for feeding material through the center of said annulus, and automatic means for operating said primary feeding means, and manually controlled means for separately operating said secondary feeding means.
50. 10. In a device of the class described, a primary feeding and packing device, a secondary non-packing feed device, a support beneath said devices movable by the material feed, and means governed by the movement of the support for stopping said primary feeding device and manual means for separately starting said secondary feeding device.
55. 11. In apparatus of the character described, a feeding tube having therein a central tube and an annular passage surrounding said central tube, and an annular shutter adapted to close the discharge end of said annular passage.
60. 12. In apparatus of the class described,

a primary feeding device adapted to feed coarse materials, a shutter adapted to stop all feed from said primary feeding device, and a secondary feeding device adapted to feed fine materials.

13. In apparatus of the class described, a primary feeding device adapted to feed the bulk of a charge for a package, and a secondary feeding device comprising a screen including a movable screen element, whereby fine materials may be sifted into the package to complete the charge.

14. In apparatus for filling and weighing

bags, means to compact the bulk of a charge into a bag including means to place under tension the walls of the portion of the bag receiving the charge, weighing means, means to relieve said tension and to place the bag on the weighing means after the bulk of a charge has been compacted therein, and means for dropping into the bag additional material while it is on said weighing means.

In testimony whereof, I affix my signature this 12th day of March 1920.

ADELMER M. BATES.
